UNITED STATES PATENT OFFICE.

HERMAN P. ANDRESEN, OF CHICAGO, ILLINOIS.

STREET STOP-LIGHT SIGN.

Application filed March 7, 1925. Serial No. 13,727.

My invention relates generally to signs for regulating vehicle traffic but relates more particularly to signs for use at street intersections.

There are in use at street intersections two general kinds of signs, one known as a start and stop light sign which controls the traffic upon two or more streets and the other type known as a stop sign, which requires traffic to come to a stop before entering the main highway or thoroughfare.

My invention relates particularly to this latter class of signs. Such signs are used where local ordinances or other traffic rules require that the vehicle come to a full stop before entering upon or crossing certain thoroughfares, such for example as a boulevard and other highways variously known as "arterial highways" and the like. Persons driving upon such through streets, arterial highways, and the like, knowing that the rules and regulations require traffic to come to a stop before entering or crossing the same rely upon that fact so that it is dangerous when a motorist enters or crosses such street without first coming to a stop. Such practice of entering a through street without stopping obtains, however, to a very considerable extent, not because the motorists are willful violators of this regulation, but very largely because under modern traffic conditions he is not given timely and proper notice with the devices hitherto devised. That is to say, many of the through street stop signs are merely a flat surface having printed thereon a notice to stop. Such signs cannot be readily observed at any reasonable distance even in the day time and, of course, are not visible at night. This led to the practice, in some instances, of placing a light in the middle of the sign for illuminating purposes. Such latter type of sign has failed, however, to solve the problem because it has resulted in merely giving a general illumination to the sign as a whole. That is to say, the warning cannot be observed at any great distance and the lettering upon the signs cannot be read until the motorist is practically upon the sign which may be too late for him to stop the vehicle as required.

Again under modern traffic conditions and with the through street stop signs hitherto used the sign may be totally obscured, as for example, when vehicles are parked adjacent such signs or are moving past the

same in the line of vision of the oncoming motorist.

The general object of my invention is to provide a through street stop light sign which shall function to warn the motorist a very considerable distance therefrom that there is danger ahead and which shall also make visible and legible to the motorist the inscription or indicia carried by the sign at a much greater distance than is possible with signs of the type heretofore devised.

More specifically it is an object of my invention to provide a sign of the type referred to which shall project a warning light at relatively great distance as by the conversion of light rays proceeding from a luminous source into a definite pencil of light and which sign shall also bear an inscription or indicia visible at considerable distance by virtue of the conversion of light, by reflection, into parallel planes extending away from the sign in the direction in which they are to be viewed.

Again, it is an object of my invention to provide a stop light sign of the character mentioned wherein a single source of light shall serve for both purposes; in which the shape of the sign shall be such as to function most efficiently and at the same time protect the parts from the elements; and which shall be of simple, durable, and relatively inexpensive construction.

My invention consists generally of a street stop light sign of such form, arrangement, and construction that the above named objects, together with others that will appear hereinafter are attainable; and my invention will be more readily understood by reference to the accompanying drawings which illustrate what I consider, at the present time, to be the preferred embodiment thereof.

In said drawings:

Fig. 1 is a front face view of a device embodying my invention.

Fig. 2 is a rear view thereof.

Fig. 3 is a view upon an enlarged scale, substantially along the line 3-3 of Fig. 1; and

Fig. 4 is a diagrammatic view of the sign in place at intersecting highways.

As here shown, the sign is composed of a member which in face view is circular in shape, but this it should be understood is by way of illustration and not by way of limitation as it may assume other shapes. The

member 1 is substantially concave in form, thus providing an inner surface 2 which is here shown as of parabolic shape. On this parabolic surface 2 I have provided the desired indicia or inscription 3 which, in the present instance, comprises the word "Stop" arcuately disposed in the upper portion of the parabolic surface and the word "Through-street" similarly arranged in the lower portion. This inscription may be formed in various ways, but I have here illustrated it as being formed by making the portion within the confines of the letters of a relatively good light reflecting character, such as a white enamel, and by making the surrounding surface 4 of a good light absorbing character such as dull black enamel or paint.

Centrally of the sign I have arranged a source of light which here takes the form of a concentrated filament incandescent lamp, of which 5 is the filament, 6 the glass bulb and 7 the base or socket. The base or socket 7 is off center with respect to the focal axis of the sign for reasons which will shortly appear and is housed within an annular housing portion 8. The housing 8 is here shown as being cast integral with the parabolic member 1 and is somewhat conical in shape terminating in a centrally disposed opening 9 through which the lamp bulb 6 projects. Surrounding the lamp bulb 6 is a tubular transparent member 10 which is held in place by a ring 11 and the long bolts 12. In the ring 11 I mount a lens 13 which is held in place by any suitable means such, for example, as a snap ring 14. The lens 13 is so formed that the light rays 15 proceeding from the source of light in a divergent manner are converted into parallel paths to form a definite pencil of light indicated by the rays 15.

Certain of the light rays 15^a pass outwardly through the transparent tube 10 where they impinge, some upon the opaque surface 4 where they are absorbed to a very large extent and some upon the relatively good reflecting surface of which the letters are formed as before described. Such light as falls upon the letters is reflected forwardly in parallel paths 15^b by virtue of the parabolic shape of the reflecting surface.

Because of the structure which I have thus provided the pencil of light from the lens 13 can be seen at a great distance and if of color character such as red indicates to the motorists that caution is required. Thereafter, but still in ample time to bring the automobile to a stop even though moving at a good rate of speed, the letters upon the sign become legible or readable. They stand out clearly and distinctly because there is a total separation of the central warning light beam from the rays which

illuminate the parabolic surface on which the inscription appears. A test of the sign has shown its marked superiority over the signs heretofore used for this purpose.

I also prefer to provide the rear of the sign with a central opening 16 in which I place a lens 17 which preferably also converts the light rays into a definite pencil of light as indicated at 18.

The purpose of the rear lens or light opening will be best understood by reference to the diagram Fig. 4 wherein 20 represents the through street, 21 the cross street and 22 and 22^a the signs upon opposite corners. The sign 22 is intended to warn motorists going in the direction of the arrow A and the sign 22^a in the direction of the arrow B. At times, however, the sign may be obscured as by an automobile 23 so that the motorist in the automobile 24 can not see sign 22. But he can see the light in the rear of sign 22^a which unless the traffic was open would give a red or other danger signal and he would probably realize that it meant to stop.

It will be observed that the single lamp thus serves a triple purpose.

It remains to be stated that the sign is supported upon a pipe 25 through which the electric wire 26 is carried to the lamp provided an underground circuit is available. If no underground circuit is available then the wires may be taken through an opening 27 in the rear of the sign, this opening being protected by a roof-like lip 104.

The concave or parabolic surface of the sign not only functions admirably in the matter of reflecting the inscription thereon but serves to protect the indicia and reflecting surface from falling objects, dirt, rain, snow and the like.

The many advantages of my invention will, without further comment, be clear to those skilled in the art to which this appertains.

I claim:

1. A street stop light sign embodying therein an incandescent lamp, a socket therefor, a parabolic wall surrounding said incandescent lamp at least in part, said lamp socket being positioned at one side of the focal axis of the sign, means for converting a portion of the light from said lamp into a projected pencil of light, said parabolic wall having an opening therein so that a portion of the light rays can be seen from the rear, said parabolic wall having light reflecting surfaces formed thereon positioned to form visible indicia.

2. A street stop light sign embodying therein an incandescent lamp, a socket therefor, a parabolic wall surrounding said incandescent lamp at least in part, said lamp socket being positioned at one side of

the focal axis of the sign, means for con- positioned to form visible indicia, and light
verting a portion of the light from said absorbing surfaces adapted to accentuate
lamp into a projected pencil of light, said said indicia. 10
parabolic wall having an opening therein In testimony whereof, I have hereunto
5 so that a portion of the light rays can be set my hand, this 24th day of February,
seen from the rear, said parabolic wall hav- 1925.
ing light reflecting surfaces formed thereon
